H. R. STRAIGHT.

APPARATUS FOR DISTILLING OIL BEARING SHALE.

APPLICATION FILED JULY 31, 1918.

1,330,014.

Patented Feb. 3, 1920.

UNITED STATES PATENT OFFICE.

HALVER R. STRAIGHT, OF ADEL, IOWA.

APPARATUS FOR DISTILLING OIL-BEARING SHALE.

1,330,014.

Specification of Letters Patent.

Patented Feb. 3, 1920.

Application filed July 31, 1918. Serial No. 247,692.

To all whom it may concern:

Be it known that I, HALVER RUFUS STRAIGHT, a citizen of the United States, and resident of Adel, in the county of 5 Dallas and State of Iowa, have invented a certain new and useful Apparatus for Distilling Oil-Bearing Shale, of which the following is a specification.

The object of my invention is to provide 10 an apparatus of simple, durable and inexpensive construction, especially designed for releasing the less volatile ingredients from oil-bearing shale.

It should be explained at the outset that 15 my apparatus is intended primarily to be used in connection with some other apparatus for distilling the more volatile ingredients from the shale, and that after the shale has been heated to a certain extent 20 sufficient to release the more volatile ingredients, it is then placed in the present apparatus for the purpose of further heating it and removing the less volatile ingredients.

25 A further object is to provide an apparatus of this kind in which the shale may be subjected to high temperatures without injury to the apparatus.

Still a further object is to provide an 30 apparatus of this kind which may be economically operated by utilizing the pre-heated condition of the shale when combined with air in measured quantities for further increasing the temperature of the 35 mass of shale by combustion of the shale itself.

Still a further object is to provide improved means for admitting fuel gas, steam and air into the interior of the shale container.

40 My invention consists in the construction, arrangement and combination of the various parts of the apparatus, whereby the objects contemplated are attained, as hereinafter more fully set forth, pointed out in my claims and illustrated in the accompanying drawings, in which:

Figure 1 shows a vertical, central, sectional view of an apparatus embodying my 45 invention.

Fig. 2 shows an enlarged, detail, sectional view, taken on the line 2-2 of Fig. 1; and

Fig. 3 shows an end elevation of the apparatus.

55 Referring to the accompanying drawings,

I have used the reference numeral 10 to indicate a cylindrical shale receptacle. This receptacle is preferably composed of an inner layer 10^a of fire-brick, and an outer layer 11 of metal. The lower end portion 60 12 is preferably flat, and the upper end portion is arched.

Arranged on the exterior of the cylindrical shale receptacle are two or more circular beveled tracks 14, which rest upon 65 and are engaged by the supporting wheels 15. There are preferably two or more of these supporting wheels 15 for each track.

For the purpose of rotating the shale receptacle there is a cylindrical rim 16, having cog teeth thereon which are engaged by and in mesh with a pinion 17 on the shaft 18 driven by an electric motor 19 or other source of power, through a worm 20, a worm wheel 21, or in any other suitable 75 manner. The cylindrical receptacle is preferably arranged at an angle of about thirty degrees relative to a horizontal line, as clearly shown in Fig. 1.

At the upper or receiving end of the receptacle is a metal sleeve 22, having an opening therein to receive the discharge end 23 of a hopper 24 for containing shale, and extended through this same opening in the sleeve 22 is a vapor pipe 25, one end of 80 which projects into the interior of the receptacle above the shale line, and its other end, communicates with an exhaust fan 26 driven by a motor 27 or in any other suitable manner, for discharging the vapors into 85 a condenser 28, which condenser leads to a settling tank 29. From this tank there are a number of discharge pipes 30, 31 and 32, by means of which the various ingredients, such, for instance, as heavy oils, paraffin 90 and ammonia liquor, may be drawn from the tank 29 after they have been settled and separated into layers within the tank 29.

At the lower or discharge end of the receptacle is a metal collar 33 fixed to the 100 receptacle to rotate therewith, and provided with a series of openings at 34, leading into the interior of the receptacle and through which the spent shale may be discharged.

105 Fixed to the central portion of this plate is a mixing nozzle 35 which projects centrally into the interior of the receptacle for a distance of approximately half the length of the shale receptacle. This mixing nozzle 110

is provided at intervals throughout its length with series of perforations 36, and secured to the outer surface thereof, adjacent to these perforations, are the circular shields 37 to prevent the shale from entering the mixing nozzle without interfering with the passage of air and gas outwardly through the mixing nozzle.

The arrows in Fig. 1 illustrate the direction of travel of the air, gas and steam within the mixing nozzle outwardly into the mass of shale.

These shields 37 are preferably supported in position by means of the blocks 37^a, as clearly shown in Fig. 2.

At the rear or lower end of the nozzle 35 is a packing box 38, into which is inserted a tube 39 which is designed to remain stationary while the nozzle and the receptacle 20 rotate freely about it in the said packing box. Mounted on a stationary bracket adjacent to the rear or lower end of the receptacle, is a discharge spout 40, arranged to receive the spent shale and to conduct it to 25 a suitable point of discharge.

Communicating with the tube 39 is a gas pipe 41, a steam pipe 42 and a valve 43 to admit air, so that steam, air and gas may be discharged into the nozzle 35, either jointly 30 or independently, as may be desired, and in any desired proportion.

In practical use, and assuming that the receptacle has been filled to the point indicated in Fig. 1 of the drawings, with oil-bearing shale that has been previously heated to such a temperature as is sufficient to release therefrom such ingredients as, for instance, gasoline, kerosene and light lubricating oils, and that the material has been 40 deposited in the receptacle at about the temperature required for releasing light fuel oils, that is about nine hundred degrees Fahrenheit, then the receptacle is rotated in the manner explained, and the air valve is 45 opened to permit a measured quantity of air to be forced into the nozzle 35 by means of the steam pipe 42 acting as an injector. The steam and air thus introduced are forced outwardly through the nozzle into the center 50 of the mass of heated oil-bearing shale, and furnish just sufficient oxygen to produce slow combustion of portions of the oil-bearing shale. This combustion of the shale itself very quickly raises the temperature 55 of the entire mass of shale to such high temperatures as are necessary in releasing therefrom the less volatile ingredients, such, for instance, as heavy oils, paraffin and nitrogen. The rotation of the receptacle 60 constantly turns over the mass of shale and prevents it from fluxing, so that the vapor and gases that have been released by the heat can readily pass upwardly to the vapor and gas chamber at the top of the receptacle. 65 The admission of steam, in addition to serv-

ing as an injector, also aids materially in the separation of the vapors and gases from the mass of shale.

In the event that the admission of air and steam alone to the interior of the nozzle is 70 not sufficient to ignite the adjacent portions of the shale, the gas pipe is opened to permit a quantity of inflammable gas to enter the nozzle 35, and this gas when ignited by the hot shale will soon bring up the temperature to the desired amount to cause the adjacent portions of the shale to burn. Obviously, the amount of heat that is generated inside the receptacle can be regulated to a nicety to suit the requirements, by regulating either the amount of gas or air that is admitted to the mixing nozzle.

One of the important advantages in connection with my invention is that in the treatment of oil-bearing shale the more 85 volatile ingredients may be conveniently and economically removed from the shale by means of an apparatus employing a cast iron conveyer for holding the shale, as these more volatile vapors may be released from 90 the shale by the application of heat at temperatures which will not injure the cast iron conveyers, whereas it is impracticable to heat the shale to such temperatures as would release the less volatile vapors, such, for instance, as the ones herein described, in a 95 conveyer of cast iron.

An apparatus for removing the more volatile ingredients is illustrated and described in a companion application, filed by 100 me on July 31, 1918, Serial Number 247,693.

In practice it is obvious that only a negligible quantity of the ingredients of the oil-bearing shale is lost in this improved apparatus, because the parts of the shale that are 105 ignited and glowing and that provide the heat for raising the temperature of the rest of the mass, are the parts that are near the discharge end, and as soon as they are burned out they are discharged from the interior of the receptacle; whereas the incoming supply of pre-heated oil-bearing shale is rapidly raised in temperature and its valuable volatile ingredients are rapidly raised in temperature and vaporized, and the 110 vapor discharged, before the combustion of the remaining carbon contents therein has 115 commenced.

I do not intend to limit the application or use of my invention solely for the purposes 120 before described, as it has a considerable degree of usefulness in its present form for roasting ore, or other purposes. In such instances, however, the material being operated on has to derive all of its heat from the 125 gas flame.

I claim as my invention:

1. In a device of the class described, an inclined heating chamber mounted for rotation, said chamber having an opening in its 130

upper end for receiving shale or the like, said chamber having in its lower end an opening for the discharge of shale, a heater nozzle projected into the interior of said 5 chamber through the lower end thereof in the axis of rotation of the chamber, means for supplying fuel and air to said nozzle, and means for rotating said chamber whereby said chamber may be rotated and the contents thereof heated from within, so that 10 portions of the shale itself may be used for combustion.

2. In a device of the class described, an inclined heating chamber mounted for rotation, means for rotating said heating chamber, said chamber having an opening at its 15

upper end for receiving shale or the like, a gas and vapor carrying tube projected through said opening a substantial distance into the upper part of said chamber where- 20 by its intake opening in the chamber is located above the level of the shale in the chamber, as said shale is agitated and moved downwardly through said chamber, said chamber having an opening in its lower end for constantly discharging shale during the 25 operation of the device, and means for heating the shale in said chamber, a hopper having a discharge member projected into said first opening.

Des Moines, Iowa, July 13, 1918.

HALVER R. STRAIGHT.
